UNITED STATES PATENT OFFICE.

AZEL C. HOUGH, OF JANEVILLE, WISCONSIN.

SHUTTLE.

1,112,799.

Specification of Letters Patent.

Patented Oct. 6, 1914.

Original application filed November 26, 1913, Serial No. 803,309. Divided and this application filed April 23, 1914. Serial No. 833,894.

To all whom it may concern:

Be it known that I, AZEL C. HOUGH, a citizen of the United States of America, residing at Janesville, in the county of Rock 5 and State of Wisconsin, have invented a new and useful Shuttle, (the same being a divisional part of my application filed in the United States Patent Office November 26, 1913, Serial No. 803,309,) of which the following is a specification.

My invention relates to improvements in shuttles employed in weaving shades, the weft of which consists of narrow fibers of wood or other substantial material, and resides 15 in certain peculiar means for acting on the jaws, which grip, hold and carry the slat, fiber, or weft-unit, to release such weft-unit, and to thrust the same violently from said jaws downwardly into the shed of the loom, or, in short, the invention resides in 20 weft-unit-liberating means, as hereinafter more fully set forth.

This invention is applicable to a loom such as that described in United States Letters Patent, No. 764,290, and to a shuttle of 25 the type employed in said loom, said shuttle being designed to carry the weft-units into the shed in the manner set forth in said patent, but being in this case provided with 30 additional parts and members, whereby the new results are attained.

The primary object of my invention is to produce a shuttle, of the class mentioned above, which is capable of handling successfully 35 the slats which form the body of the fabric or shade, or the weft-units, even though such weft-units be very narrow and light in weight. With this shuttle weft-units of any width, even the narrowest, can 40 be quickly, accurately and positively placed and deposited in the shed of the loom.

Other objects and advantages will appear in the course of the following description.

I attain the objects and secure the advantages 45 of my invention by the means illustrated in the accompanying drawings, in which—

Figure 1 is a side elevation, in partial section or partially broken away, of a shuttle 50 which embodies a practical form of my invention; Fig. 2, a bottom plan of said shuttle; Fig. 3, a cross-section taken on lines $\alpha-\alpha$, locking in the direction of the associated arrow, in Fig. 1, and, Fig. 4, an end ele-

vation of said shuttle, the foremost parts of 55 the same being in cross-section.

Like parts throughout the several views are designated by like numerals of reference.

Although I have illustrated and will presently describe in detail a practical form of my invention, I do not desire or intend to be thereby restricted unduly, since various modifications and changes in the shape, size, arrangement of parts, and details of construction 60 may be made without departing from the nature or spirit of said invention.

Since the shuttle travels first in one direction and then in the other, carrying with it each time a weft-unit, the new elements 65 are provided at both ends of said shuttle, but such elements at one end are duplicates of those at the other end and entirely independent thereof.

In the first view a portion of the body of 75 the shuttle at the right-hand end is broken away to disclose fully the mechanism provided at such end.

The shuttle, shown in the drawings, comprises a body 1 having a bottom plate 2 80 with terminal projections or extensions 3—3, and provided at the ends underneath with gripping members, for the weft-units, consisting of resilient jaws 4—4 and 5—5. The body 1 is designed to travel in the raceway 85 of a loom, and the plate 2 is provided adjacent to its longitudinal edges with shoes 6—6 that are adapted to slide on the raceway track. Each pair of jaws 4 and 5 is located beneath one of the extensions 3, and 90 the jaws in each pair are designed to have one end of a weft-unit, such as is shown at 7, in Fig. 1, forced between them, and firmly to grip and hold said unit and to carry it 95 into the shed of the loom, when the shuttle is shot. Each of the jaws 5 is secured to a lug 8 that extends downwardly from the bottom of the plate 2, while the jaws 4 are formed by the terminals of a resilient strip 9 secured to a central lug 10 that also depends from said plate bottom. The parts 100 thus far described are similar to corresponding parts set forth in the hereinbefore-mentioned patent.

In each end of the shuttle body 1 is a slot 11, and pivotally mounted at 12 within said slot is a releaser and projector 13 for the weft-units. Each releaser and projec-

tor 13 has a cam edge 14 which extends above the slot 11 within which said releaser and projector is pivoted at its inner terminal, and such releaser and projector also has 5 a finger 15 which extends out of the open end of such slot and turns downwardly to project through an opening 16 in the adjacent extension 3. A stop 17 is placed across each slot 11, near the outer end thereof and 10 above the inner end portion of the finger 15 of the releaser and projector within such slot, to limit the upward movement of said releaser and projector, which latter is normally held against said stop by means of a 15 spring 18. Each spring 18 has its base resting on the plate 2, and is received in one of the recesses 11, the sides of which latter are chambered, as indicated at 19, to accommodate said spring, and said spring is also 20 received in a slot 20 provided for it in the releaser and projector which is actuated by said spring. A tongue 21 depends from the top of the slot 20 in each releaser and projector to center or maintain in proper position the upper terminal of the spring 18 in such slot.

Normally the free end of each finger 15 contacts with the jaws 4 and 5 below, and the latter are cut out a little, as shown at 30 22-22 in Fig. 4, to receive such end, and to facilitate the operation of said finger, as hereinafter explained. To the same end, the free terminal of each finger 15 is rectangular or straight across, as appears in Fig. 4.

35 In practice, projections, which may be in the form of rolls, are located in the paths of the cam edges 14 of the releasers and projectors 13, and so arranged as to cause said releasers and projectors to be actuated downwardly against the resiliency of their 40 springs 18, when said releasers and projectors pass under said projections or rolls. One such roll is represented at 23 in the first view. Each of these rolls is so located as 45 to operate the releaser and projector 13 at the inner end of the body 1, or the end of such body that is last to pass through the shed, just before the shuttle arrives at its limit of travel in either direction.

50 The releasing and projecting members 13 are by preference relatively offset, as are the actuating or depressing members therefor, in order to avoid unnecessary friction, action and wear.

55 In operation, when the shuttle approaches either end of its travel, the inner releaser and projector 13 encounters the depressing member (as the roll 23), which is 60 in the path of the cam edge 14 of said releaser and projector, is swung downwardly on its pivot 12, as it rides beneath said member, and with its finger 15 forces apart the jaws 4 and 5 below and violently projects the weft-unit (as 7) downwardly into the 65 shed. The releaser and projector is thus de-

pressed against the resiliency of its spring 18, and the latter acts to return said releaser and projector to inactive position against the associated stop 17, as soon as the operating roll is passed, and by the time the shuttle arrives at the extreme end of its travel in the direction in which it is assumed to be moving. As observed above, the depressing rolls may and preferably should be so hung that, when the shuttle is projected from the opposite end of its travel, the releaser and projector which was just actuated is unaffected, this being true also of the other releaser and projector upon its return after being actuated to deposit a weft-unit in the shed.

Briefly stated, it may be said that the member 13 at the right-hand end of the shuttle is actuated by the roller 23 which is at the left-hand end of the loom, and that the member 13 at the left-hand end of the shuttle is actuated by a similar roller which is at the right-hand end of the loom.

In Fig. 1, it may be assumed that the shuttle is traveling to the left and has proceeded far enough for the right-hand releaser and projector 13, which is to act on the weft-unit 7 carried by said shuttle, to contact with the roll 23 which is in the path of the cam edge 14 of said releaser and projector, when said releaser and projector will be actuated downwardly, by said roll, to open the jaws 4 and 5, which have said weft-unit in their grasp, and thrust said weft-unit from said jaws.

In Fig. 2, the right-hand jaws 4 and 5 are shown fully open by the associated and contacting finger 15, as is the case when the right-hand releaser and projector 13 arrives with the high part of its cam edge 14 directly beneath the roll 23. Obviously, the thickness of the jaw-engaging portion of either finger 15 must exceed that of any weft-unit, if such finger is to spread or separate still more the jaws 4 and 5 with which the same coacts, as well as force such unit from between said jaws. In some cases, however, the aforesaid jaw-engaging part might be of the same thickness as that of the weft-unit, or possibly even of less width.

Although this invention is practicable for wide weft-units, it is especially well adapted for weft-units which are too narrow to project beneath the spring jaws far enough to be removed or knocked out by the means shown in said Patent, No. 764,290. This is clear when it is seen that, if the spring jaws were of sufficient width to hold firmly a weft-unit when it is carried swiftly through the course provided for the shuttle, that is, the raceway of the loom, they would be too wide to permit a narrow weft-unit to project a sufficient distance beneath said jaws to be released in the old way and by the old means. Moreover and in any event, any of

these weft-units can more accurately and to better advantage be introduced into a shed through the medium of a downward thrust than through the medium of an endwise thrust.

There is sufficient clearance between the top of the plate 2 and of each extension 3 and the bottom of each releaser and projector 13 and finger 15, when said finger is raised against the stop 17 therefor, to allow for the necessary amount of movement which said releaser and projector receives from the associated roll 23 at the time the shuttle carries said releaser and projector into position to deposit a weft-unit, such amount of movement being also sufficient to open fully the jaws 4 and 5, with which said finger is in engagement, and positively to thrust the weft-unit, held by said jaws, downward with the desired force.

The springs 18 must, of course, be sufficiently strong to raise the releasers and projectors 13 and draw their finger extremities from between the jaws 4 and 5, as soon as the work of liberating the weft-units is finished in each instance.

What I claim as my invention, and desire to secure by Letters Patent, is—

1. A shuttle, of the class described, provided with holding means for weft-units, and further provided with means for forcing such units from such holding means.

2. A shuttle, of the class described, provided with holding means for weft-units, and further provided with means for forcing such units from above from such holding means.

3. A shuttle, of the class described, provided with separable holding means for weft-units, and further provided with means for separating said holding means and en-

gaging such units to release and positively eject the latter.

4. A shuttle, of the class described, provided with separable holding means for weft-units, and further provided with means for separating said holding means and projecting a weft-unit therefrom.

5. A shuttle, of the class described, provided with resilient separable holding means for weft-units, and further provided with means for forcibly ejecting such units from such holding means.

6. The combination, in a shuttle, with a body provided with weft-unit-gripping jaws, of a movable member carried by said body, and having a part which is brought into operative relation to a weft-unit held by said jaws to eject the same.

7. The combination, in a shuttle, with a body provided with weft-unit-gripping jaws, of a movable member carried by said body, and having a part which is in operative relation to said jaws and to a weft-unit held thereby, and adapted positively to eject such weft-unit.

8. A shuttle comprising a body provided with weft-unit-gripping jaws, and a spring-pressed member carried by said body, such member having a weft-unit-liberating and ejecting part, and also having an actuating part.

9. A shuttle comprising a body provided with two pairs of weft-unit-gripping jaws, and a pair of members carried by said body, such members having weft-unit-liberating parts, and also having actuating parts, which latter are in different planes.
